ABSTRACT

Food products supported on trays, of the clear or opaque variety, are fed, either manually or automatically, between plastic webs which constitute an overwrap for the tray and a product carried thereby. The plastic webs follow paths which intersect and they are joined along a transverse line by heated sealing and cutting mechanisms. Tray supported products, for convenience called units, are fed toward and past the juncture of the webs, while the webs are unwound from their respective parent rolls, enveloping the unit to be packaged therebetween. Thereafter the longitudinal edges of the webs adjacent the unit are heat sealed and cut while simultaneously therewith the webs are transversely joined along transversely spaced lines adjacent the trailing end of the unit resulting in a hermetically sealed unit and joining of the web ends to provide a juncture for a subsequent package.

PACKAGING MACHINE AND METHOD

SUMMARY OF THE INVENTION

The present invention discloses a packaging machine incorporating two parent web rolls which are simultaneously and intermittently unwound. The unwound webs are firmly held along their longitudinal edges by polished anvils and confronting endless belts and chains which follow curvilinear paths through part of their orbit. When web of the stretch type is utilized the paths followed by the chains are oriented to gradually diverge so that progressive stretching of the film takes place along an imaginary line, which is approximately at the intersection of the curvilinear paths. The end of each web is joined by a heated bar thus in effect producing one continuous web.

When packaging tray loaded fresh meat, the tray is advanced to the welded juncture of the webs either manually or automatically. Means may be provided, such as a photo cell or equivalent detecting device, for initiating unwinding of the webs at a speed substantially equal to the speed at which the tray or unit is transported. Continued movement of the tray brings the leading edge in contact with the joined webs and, as the webs unwind, the unit to be packaged is located therebetween. This stage of the process may be characterized as enveloping the unit in a U-shaped or looped elongation of a flexible web.

After the tray is completely enveloped by the web, unwinding of the webs is interrupted and the tray is momentarily held stationary to allow operation of sealing mechanisms which bring the overlying longitudinal margins of the web together and, while so held, heated cutting and sealing devices join the webs laterally inwardly of its margins to produce the longitudinal side seams. Simultaneously with production of the side seams a portion of the web adjacent the trailing edge of the package is sealed and centrally cut which completes overwrapping of the tray. The cut transverse seam made adjacent the trailing edge of the package leaves a sealed portion which again joins the two webs together in preparation for packaging a subsequent tray.

Since the sealing mechanism for producing the longitudinal side seals and the seal adjacent the trailing end of the package have, in any particular design, limitations as to package length and width, packages having a variety of length and width dimensions below the maximum, as dictated by the sealing mechanism, can be packaged at random. Accordingly, this provides the degree of versatility required in those packaging situations encountered in supermarkets.

In accordance with the present invention a unique web gripping arrangement is provided which relies upon the adhesion of the film to polished blocks or anvils carried by sprocket chains. It has been discovered that by properly treating the surface of the anvils, which have a highly polished surface, over which the web is disposed, clamping of the web edges either by belts or individual clamps may be unnecessary. It has also been found that the adhesion of the web to the treated surface of the anvils is sufficient to prevent slipping of the web as long as the web lies substantially in the plane of the anvil surfaces. As will be explained in greater detail hereinafter, the web will be retained by the anvils when a positive acute angle is defined by the anvil surface and web while a negative angle (one which contributes to peeling of the web from the anvil surface) will not retain the web on the anvils.

Further in accordance with this invention a web sealing mechanism is provided which is operated sequentially to grip the web adjacent the package margins, cut the web to effect relaxation thereof and seal the relaxed web while the web around the package is held under tension. It was found that attempts to seal the web in stretched condition resulted in poor seal quality and in certain cases the web failed to seal at some areas.

It is a further feature of this invention to provide cooperating pairs of sprocket chains and V-belts, or equivalent mechanical devices, for gripping the web edges in those in-

stances where the web material does not adhere to the polished anvils. An example of such web is cellophane. In handling web of this nature the edges are clamped between flexible tension devices, such as chains or belts or combinations thereof, which are in firm engagement. The clamping force may be adjusted as desired to insure web retention in those instances where the web is laterally stretched.

BRIEF DESCRIPTION OF THE DRAWINGS

- 10 FIG. 1 is a perspective view of the packaging machine constructed in accordance with the principles of the present invention,
- 15 FIG. 2 is a front elevation, on an enlarged scale, of the packaging machine of the present invention,
- FIG. 3 is a side elevation of FIG. 2,
- 10 FIG. 4 is a diagrammatic view showing the drive arrangement for feeding the webs and for feeding the package,
- 20 FIG. 5 is a fragmentary enlarged detail, as viewed in the direction of the arrows 5-5 of FIG. 3, of the web feed conveyor,
- FIG. 6 is a transverse section taken along the line 6-6 of FIG. 5,
- 25 FIG. 7 is an enlarged plan view of the sealing mechanism,
- FIG. 8 is a side elevation of the web sealing mechanism showing the top and bottom sealing heads in retracted position,
- 30 FIG. 9 is a horizontal section taken along line 9-9 of FIG. 8 showing the bottom sealing head,
- 30 FIG. 10 is an enlarged section, taken substantially along line 10-10 of FIG. 7, showing the retracted position of the top and bottom sealing heads prior to being actuated to seal a package,
- 35 FIGS. 11, 12 and 13 illustrate the progressive action of the sealing heads during sealing of a package and show, respectively, bringing the webs in firm contact, cutting the webs, and sealing them,
- 40 FIG. 14 is a fragmentary perspective, located in rotated planes, showing the construction of the upper and lower sealing heads at the juncture of the side seal and the trailing seal,
- 45 FIG. 15 is an enlarged section, taken along line 15-15 of FIG. 7, showing on an enlarged scale, the construction of the top and bottom sealing bars for producing the seals at the trailing edge of the package and for joining the top and bottom webs together,
- 50 FIG. 16 is a section, taken substantially along line 16-16 of FIG. 7, of the upper and lower sealing heads,
- 50 FIG. 17 is similar to FIG. 16 but shows the upper and lower sealing heads in contact which is the position assumed during the sealing operation.
- 55 FIG. 18 is an enlarged section taken substantially along line 18-18 of FIG. 7 showing the manner in which the upper gripping bar is guided for rectilinear movement and the means for gripping the web during the sealing operation,
- 60 FIG. 19 shows the relationship of parts when the upper sealing head is in firm contact with the lower sealing head,
- 60 FIG. 20 is an enlarged plan of a package infeed mechanism,
- 65 FIGS. 21, 22, 23 and 24 illustrate the progressive action of the package infeed mechanism for feeding a package to the sealing station,
- 65 FIGS. 25, 26, 27 and 28 are diagrammatic enlarged perspectives illustrating the steps involved in packaging a product,
- 65 FIG. 29 is a schematic of the control circuit of the packaging machine,
- 70 FIG. 30 is a diagrammatic perspective of a modification which may be applied to the upper stretch frame when it is desired to effect longitudinal as well as lateral or transverse stretching of the web,
- 70 FIG. 30A is side view of the modification of FIG. 30 adapted to the lower stretch frame, and
- 75 FIG. 31 is a diagrammatic perspective of another modification, which can also be applied to each stretch frame, when it

is desired to prevent lateral or transverse stretching of the web.

GENERAL ARRANGEMENT

The general arrangement of the machine embodying the present invention is shown in perspective in FIG. 1 and it is identified by the general numeral 20. Broadly, the machine comprises a bottom stretch frame 22 having laterally spaced and interconnected diverging side frames 22a and 22b. The divergent orientation of frames 22a and 22b is best illustrated in FIG. 2. Supported above the bottom stretch frame 22 is an upper stretch frame 24 including side frame members 24a and 24b which are also oriented in diverging relationship. Each of the stretch frames rotatably support unwind shafts 26 and 28 rotatably mounted, respectively, on the lower stretch frame 22 and the upper stretch frame 24. A bottom web roll BWR of packaging web BW is mounted on the unwind shaft 26 while a top web roll TWR of packaging web TW is mounted on the unwind shaft 28. The top and bottom webs are unwound and transversely stretched by a web feed arrangement comprising V-belts 32 and 34 associated with the upper stretch frame 24 and cooperating sprocket chains 36 and 38 also associated with the upper stretch frame 24. As shown in FIG. 2 the lower stretch frame 22 also includes V-belts, identified as 40 and 42, and sprocket chains 44 and 46. Since the arrangement and cooperation of the V-belts and sprocket chains are identical in each stretch frame 22 and 24 the description herein will be confined to the upper stretch frame 24.

The longitudinal edges or margins of the web TW are received between the chains 36 and 38 and the V-belts 32 and 34, to, in part, initiate unwinding of the web from the web roll. Since the distance between the chains 36 and 38 progressively increases, the web TW is transversely stretched with the maximum lateral or transverse stretching occurring when the chains 36 and 38 start traversing the horizontal reach defined by sprockets 92 rotatably mounted on the upper stretch frame 24.

At the juncture of the lower stretch frame 22 and the upper stretch frame 24 a web sealing mechanism, indicated by the general numeral 50, is provided for producing longitudinal and transverse seals about the unit to be packaged. The sealing mechanism includes a lower sealing head 52 and an upper sealing head 54 (FIG. 8) which are reciprocated simultaneously toward and away from each other in response to the presence of a package between the webs. When the sealing heads 52 and 54 come in contact with each other, the top and bottom webs are joined along the line J (FIG. 1) which is approximately in the plane containing the juncture of the bottom and top stretch frames 22 and 24. Items or units to be packaged are fed into the machine in the direction of the arrow A on an infeed table 56. The package is fed to make contact with the looped portion of the webs at the juncture J thus enveloping the package or item to be packaged between the webs BW and TW. The item to be packaged together with the sealed loop and of the webs is transported within the confines of the sealing mechanism 50. After the item has moved a sufficient distance to come within confines of the sealing mechanism 50 the upper and lower sealing heads 54 and 52, respectively, are reciprocated toward each other joining the top and bottom webs along lines inwardly adjacent the marginal edges thereof and along a transverse line adjacent the trailing edge of the package. The transverse seal is severed, when made, to form both the trailing end of the leading package and the leading end of the next package. Since the longitudinal seals are spaced laterally inwardly of the web edges a strip of waste material is produced. Such waste, which comprises a band of film S (FIG. 25), is wound up on spools 60 rotatably mounted on arms 62 carried by the upper stretch frame 24.

Referring to FIG. 1 it will be observed that the packaging apparatus is provided with drive means generally indicated by the numeral 64 which includes a motor 66 driving a chain and

sprocket arrangement 68 which is connected to drive the web feed chains 36 and 38, of the upper stretch frame 24, and the chains 44 and 46, of the lower stretch frame 22. The drive is connected to a sprocket chain 70 mounted adjacent and on one of the longitudinal edges of the infeed table 56. The chain 70 is driven by a sprocket 72 and is trained about an idler sprocket 74. The idler sprocket 74 is mounted on a bracket 76 (FIG. 1) secured to the infeed table 56. Attached to the chain 70 is a product pusher bar 78 which directs products to be packaged toward the web juncture J. In moving the product toward the webs, resilient product centering shoes 80 are encountered which center the product before it is enveloped by the webs. Inspection of the FIG. 2 will reveal that the drive motor 66 is mounted on a plate 82 which is secured to the side frame members 22a and 22b at a slight angle with respect to the horizontal. Further and more detailed explanation of the drive for the packaging machine of the present invention will be given in connection with FIG. 4.

According to the above description of the general arrangement of the packaging machine of the present invention it should be appreciated that it provides automatic packaging of articles of random size and shape between two hermetically sealed webs which minimizes, particularly those packages having certain dimensions of length and width, the amount of film required to produce a marketable package. Further the machine of the present invention provides a unique method of holding the margins of the film while it is being stretched and maintains the film of the package in the stretched condition until the package is hermetically sealed. After the package tray is enveloped and sealed between a pair of webs, and the stretching force is removed, the film assumes a tightly stretched condition over the packaged product.

35

WEB DRIVE

As indicated previously the lower and upper stretch frames 22 and 24, respectively, are substantially identical in construction and such similarity in construction also relates to the frame structures and the manner in which the V-belts 32, 34, 40 and 42 and the chains 36, 38, 44 and 46 are related and driven. Accordingly this portion of the description will be confined to the upper stretch frame 24 while any differences that exist will be specifically pointed out. As shown in FIGS. 1, 2 and 3 the upper stretch frame 24 includes a plurality of interconnected structural members which support the various sprockets and pulleys for the chains 36 and 38 and the V belts 32 and 34. Each of the side frames 24a and 24b of the upper stretch frame 24 takes the general form of a truncated right triangle including a vertically extending member 84 secured at its upper end to a horizontal member 86 and a member 88 extending at an acute angle relative to the member 84. As shown on FIG. 3, arcuate chain guiding tracks 90, for guiding the chains 36 and 38, are secured to the members 88. Reference to FIG. 2 will reveal that the tracks 90 assume the divergent orientation of the side frame members 24a and 24b.

Each of the chains 36 and 38 carries a series of closely adjacent anvil or web gripping blocks 100 spaced in close proximity along the entire length of the chains 36 and 38. As shown in FIGS. 5 and 6 the blocks are provided with a V groove 102 and a highly polished smooth surface 104 (herein shown as a flat surface although surfaces of other configurations may be utilized) against which a web adheres. While the particular technical reasons for firm adherence of the web to the polished surface 104 of the anvil blocks 100 do not appear to be completely understood, in practice it has been found that the adherence of PVC web is sufficient to effect stretching thereof without significant contribution by the V belts 32 and 34. As the belts 32, 34 leave the sprockets 94, they pass up over pulleys 105 and on to sprockets 96 (FIGS. 1 and 3).

The construction lines R and T in FIG. 6 represent, respectively, the plane containing the surface 104 of the anvils 100 and the plane containing the web TW in the vicinity of the an-

75

vil. The angle between the lines R and T is identified as c and is defined as a positive angle. Experimental results thus far indicate that webs of certain varieties, particularly stretch web, will adhere to the anvil surfaces 104 as long as the angle between the planes is positive and that the limit of adhesion, that is web retention, occurs when the angle is 0°. Negative angles develop a "peeling" action and accordingly web retention, by the action of the anvils alone, fails. It has been determined that PVC film exhibits excellent retention qualities. In fact its retention qualities will allow stretching of the web without the assistance of the V-belts.

Referring to FIG. 4 it will be observed that a diagrammatic perspective showing of the packaging machine drive is illustrated. To avoid confusion the frame structure and the sealing structure is not shown. The lower stretch frame 22 includes pairs of transversely aligned sprockets 106, 108 and 110 and belt pulleys 105a assuming the same relative position on the lower stretch frame 22 as the sprockets 92, 94, 96 take on the upper stretch frame 24. The motor 66 and the drive means 64 drive a sprocket chain 112 by means of an output sprocket 114. The sprocket chain 112 is trained to make contact with a tensioning sprocket 116, a sprocket 118, mounted on a shaft 120 that also carries a clutch 122 and another sprocket 124. The chain 112 also is trained about a sprocket 126 connected to a shaft 128 on which the drive sprocket 72 of the product pusher chain 70 is mounted. Another tensioning sprocket 130 also is in mesh with the sprocket chain 112.

On a main flexible transverse drive shaft 132, which has secured thereon the sprockets 106, a sprocket 134 is secured. The sprocket 134 is driven by a sprocket chain 136 which is trained about the sprocket 124 that is intermittently rotated in response to actuation of the clutch 122. Rotation of the shaft 132 causes movement of the film conveyor chains 44 and 46 and obviously the rotation of the pairs of transversely aligned sprockets 108 and 110.

The right rear sprocket 108 (FIG. 4) is keyed to a shaft 138 which also has mounted thereon a pulley 140 driving a V-belt 142 which in turn is trained about a pulley 144 keyed to a shaft 146 which rotates an elongate conveyor drive roller 148. In cooperation with an idler roller 150, the roller 148 drives a conveyor belt 152 which discharges packaged products from the sealing station of the packaging machine.

Driving of the chains 36 and 38 of the upper stretch frame 24 is effected by the shaft 138 which drives a sprocket 154 through a right angle drive gear box 156. A sprocket chain 158, trained about the sprocket 154, drives a sprocket 160 which is connected to the sprocket 94 through another right angle gear box drive 162. The driving force supplied by the sprocket 94 moves the chain 38 in the direction indicated by the arrows. Driving of the chain 38 causes rotation of the sprocket 96 in meshing engagement therewith and, by virtue of a flexible transverse shaft 164, the other sprocket 96 then drives the chain 36 concurrently with the chain 38.

Accordingly, it will be realized that the web drive chains 44 and 46 on the stretch frame 22 and the web drive chains 36 and 38 on the upper stretch frame 24 are driven simultaneously and to the same extent in order to supply an amount of stretch web for packaging which is dictated by the size of the product to be packaged.

WEB SEAL MECHANISM

In accordance with the present invention the sealing mechanism 50 completely encloses the product to be packaged after it has been inserted into the loop formed by the joined webs. The mechanism makes line seals adjacent the lateral edges of the package and adjacent the trailing edge which thereby results in a hermetically sealed package. As pointed out above, a seal is made adjacent the trailing edge of the package to produce the juncture J. While the details of the sealing mechanism will be specifically pointed out hereinafter, preliminarily it is pointed out that the design of the sealing mechanism 50 provides an acceptable seal while the web is in

tension or in a stretched condition around the package tray. As a result the sealing mechanism brings the superposed web portions in firmly clamped contact at a point intermediate the web conveying chains and the package. The marginal portions 5 of the overlaying webs are then cut, outward from where they are clamped to relax the tension, and are thereafter sealed. Meanwhile, the web surrounding the package tray is held under tension.

10 The construction and certain operational sequences of the sealing mechanism 50 are shown in FIGS. 7-19.

15 Referring first to FIGS. 7 and 8 it will be seen that the sealing mechanism 50 has generally rectangular configuration. As previously described the sealing mechanism includes a lower sealing head 52 and an upper sealing head 54. The lower sealing head 52 includes laterally spaced bearing blocks 166. The bearing blocks 166 are rigidly attached, by means of small angle brackets 170, to structural members 168, joining the lower and upper stretch frame 22 and 24, while similar small 20 angle brackets 172 rigidly attach the upper bearing blocks 174 (FIG. 8) to the structural members 168. Each of the bearing blocks 166 rotatably support transversely aligned and longitudinally spaced shafts 175 each of which have fixed thereon sprockets 176a, and 176b. Each shaft also has fixed thereon cams 178, the profile of which is shown in FIGS. 16 and 17, which, as will be explained presently, reciprocate the lower sealing head 52 toward and away the film.

25 The reciprocating portion of the lower sealing head is generally indicated by the numeral 180 and, as shown in FIG.

30 9, it is generally rectangular in configuration. The frame structure 180 comprises transversely spaced support rails 182 (FIG. 10) interconnected at one end by a transverse seal bar structure 184 and at the other end by a tie rail 186. Each of the rails 182 rotatably support cam follower rollers 188 which are in rolling engagement with the cams 178. Representative sections of the support rails 182 are shown in FIGS. 10, 11, 12 and 13. Referring to these figures it will be observed that the rails 182 have an elongated strip 190 secured thereto which in part slidably retains an elongate anvil bar 192 slotted to receive a rubber insert 194. The anvil bar 192 is mounted for movement relative to the support rails 182 and is biased upwardly by springs 196 (only one of which is shown) spaced at longitudinal intervals on the rails 182. The anvil bar 192 is 35 movably fixed to the support rails 182 by providing transverse slots 198 through which extend pins 200. As shown in FIG. 10 the anvil bar 192 is in its raised position by virtue of the force exerted by the springs 196. When the sealing heads 52 and 54 are brought in firm engagement (FIG. 13) the anvil bar 192 is 40 moved against the force exerted by these springs 196 to thereby regulate the sealing pressure exerted on the web.

45 To insure linear vertical movement of the lower sealing head 52 vertically extending guide channels 202 are rigidly mounted to the lower bearing blocks 166. Rollers 204 are 50 fixed to the support rails 182 and are slidably received within the guide channels 202. Thus the vertical reciprocation imparted to the lower sealing head by the cams 178 is constrained to follow a linear path by virtue of the cooperation of the guide channels 202 and the rollers 204.

55 Rolling contact between the cam follower rollers 188 and the cams 178 is maintained by virtue of tension springs 206 (FIG. 16) having one end looped around pins 208 mounted on brackets 210 and the other end held by pins 212 located in bores 214 in which the springs 206 are disposed.

60 The upper sealing head 54 shown in FIGS. 7, 8, 16 and 17 has substantially the same configuration as the lower sealing head, and the manner in which reciprocating motion is imparted thereto simultaneously with the lower sealing head is 65 generally substantially similar.

66 The upper sealing head 54 is also provided with a guide arrangement which insures rectilinear reciprocation thereof. Referring to FIGS. 7, 16 and 17 it will be observed that the rails 226 rotatably support rollers 205 received in guide channels 207 rigidly attached to the bearing blocks 174.

With reference to FIGS. 7, 8, 10, 16 and 17 it will be observed that the upper sealing head is also provided with pairs of transversely spaced shafts 214 on each of which is keyed, or otherwise suitably secured, sprockets 216a and 216b. The shafts 214 are rotatably mounted in the bearing blocks 174 which serve the similar purpose and are a similar configuration as the lower bearing blocks 166. On the inner end the shafts 214, crank arms 220 are suitably rigidly mounted and the end of each crank arm carries a roller 222. Each of the rollers are located within elongated slots 224 formed in laterally spaced rails 226. When the drive for the sealing head mechanism is actuated, as will be presently explained, simultaneous rotation of the shafts 214 is effected, in turn, simultaneously rotating the crank arms 220. Rotation of the crank arms causes reciprocation of the upper sealing mechanism 54.

The side rails 226 are connected at one end by a transverse seal bar structure 228 and at the other end by a tie bar 230. Mounted inwardly adjacent each of the side rails are elongate web clamps 232 tied to the side rails by brackets 234. As shown in FIG. 8 the brackets 234 are rigidly attached to the rails 226 by screw fasteners 236 while the web clamps 232 (FIG. 8) are tied to the bracket 234 by pins 238 (FIG. 10) extending through a clearance hole in the brackets 234 and surrounded by a compression spring 240. During the sealing operation the web clamps 232 move relative to the side rails 226 in order to effect clamping of the web before it is cut and sealed.

The sequence of operations is shown in FIGS. 10, 11, 12 and 13. In FIG. 11 the relationship of parts is shown after the web is gripped between the elongate strip 190, of the bottom sealing head 52, and the web clamp 232, of the upper sealing head 54. Continued movement of the upper sealing head 54 results in compression of the springs 240 to thereby grip the web. The side rails 226 continue their downward movement toward the support rails 182 to effect cutting and then sealing of the web. The web clamps 232 are guided for rectilinear movement relative to the side rails 226 by rollers 242 rotatably mounted on short stub shafts 244 secured to the web clamps 232. The rollers 242 travel within guideways 246 (FIGS. 18 and 19) formed at each end of the side rails in the general vicinity of the brackets 234.

Referring again to FIG. 10 it will be observed that the side rails 226 have mounted, on the lower surface thereof, by means of fasteners 248, a cutting and sealing bar 250 heated by an elongate cylindrical heating element 252. The cutting and sealing bar 250 is provided with a projecting blade like portion 254, which serves to cut the web, and a seal bar 256 which is heated by the element 252.

As shown in FIGS. 11, 12 and 13 the sequence of operation involves, respectively, clamping of the web between the web clamps 232 and the strip 190 along the line adjacent the edge of the product, cutting of the webs by the projecting portion 254 thereby relaxing the tension on the film and then firm engagement between the seal bar 256 and the rubber anvil 194. After a sufficient dwell time, as dictated by the physical properties of the web, the sealing heads are retracted to their original position.

The seal bar structure 228 has a somewhat different arrangement since it must not only make the seal adjacent the trailing edge of the package but also make the seal for rejoining the top and bottom webs to produce the juncture J. As mentioned previously the seal bar structure 228 will operate in the same sequence as the web clamps 232 and the side rails 226. To achieve such relationship the seal bar structure is provided with transversely spaced clamping rails 258 and 260 which are tied together to form a rigid structure by bolts 262 extending through tubular spacers 264. The rail 258 is rigidly secured in any suitable manner to the web clamps 232. Located between the clamping rails 258 and 260 is a sealing and cutting bar 266 having an elongate cylindrical heater 268 located therein and carrying laterally spaced web engaging sealing tools 270. The bar 266 is formed with a projecting blade like portion 272 serving to sever the webs after they

have been clamped. To connect the sealing and cutting bar 266 with the sealing and cutting bar 250, blocks 274 (one of which is shown in FIG. 14) are provided and they are tied to the side rails 226 by screw fasteners 276 (FIG. 7) and to the sealing and cutting bar 266 by screw fasteners 278.

The transverse seal bar structure 184 (FIG. 9) of the lower sealing head 52 is shown in cross section and enlarged in scale in FIGS. 14 and 15. While the seal bar structure 184 is integral with the anvil 192, it is separately described for ease of description. Referring first to FIG. 15 it will be observed that the transverse seal bar 184 comprises a rail 280 formed with an upwardly extending web section 282 located substantially intermediate its side surfaces. Elongate strips 284 and 286 are fastened to the rail 280 by bolts 288. The rails 284 and 286 make contact with the clamping rails 258 and 260 of the upper seal bar 228. In channels defined by the web section 282 and the rails 284 and 286, elongate web sealing anvils 290 are disposed and are associated with springs (not shown) for urging the anvils upwardly with such upward movement being limited by pins 292 (only one of which is shown in FIG. 15) passing through the web section 282 and located in small slots 293 formed in the web sealing anvils 290. Each of the web sealing anvils 290 support and captively retain, with the assistance of strips 284 and 286, resilient rubber like inserts 294 which make contact with sealing tools 270 of the upper transverse seal bar 228.

In the lower and upper transverse seal bars 184 and 228, respectively are shown in FIG. 15 in the process of severing and sealing the top and bottom webs TW and BW. A product P, supported on a tray U, is in the process of being hermetically sealed by the sealing mechanism 50, and, as mentioned previously, the seal formed on the trailing edge of the package is formed concurrently with a seal for joining the top and bottom webs together to produce the junction J. Accordingly the upper transverse seal bar structure 228 and the lower seal bar structure 184 cooperate to form closely longitudinally spaced transverse seals. In operation when the upper and lower transverse seal bars 228 and 184 are brought in contact assuming the relative positions shown in FIG. 15, the top and bottom webs are gripped between the clamping rail 258 and the strip 284 along a transverse line adjacent the trailing edge of the package and along a line parallel thereto by the clamping rail 260 and the strip 286. Since the sealing and cutting bar 266 is rigidly attached to the side rails 226 by the blocks 274 and accordingly its blade like portion 272 passes beyond the plane in which the webs are gripped when the springs 240 are compressed, cutting of the top and bottom webs takes place after they are firmly gripped. In FIG. 15 the webs are shown severed and in the process of being heat sealed. After the webs have been severed the sealing tools 270 are firmly engaged with the rubber inserts 294 to effect sealing of the web along closely adjacent transverse lines. The seal produced in joining the top and bottom webs is indicated by the letter J.

The phenomenon of web retention explained above in connection with the anvils 100 is also utilized by the sealing heads 52 and 54. With respect to the longitudinal seals made by the interaction of the seal bars 250 with the anvils 192 the web clamps 232 have a wedge shaped portion 232a which is highly polished in order to further progressively stretch the web until it comes in contact with the strip 190 which is also highly polished. Thus before the webs are sealed the web portions intermediate the anvils 100 and the package (FIG. 10) are further stretched.

Further stretching of the webs occurs at the trailing edge of the package since the clamping rails 258 and 260 have web-engaging portions 258a and 260a with highly polished surfaces as do the strips 284 and 286. When the web is engaged by these polished surfaces, no slipping or relative movement occurs.

To prevent possible tearing of the bottom web BW when the sealing heads 52 and 54 are driven toward each other, a strip 286a, mounted adjacent the polished strip 286, is provided. The surface of strip 286a is treated so that possible retention

of the web thereby does not occur. Therefore before the bottom web BW comes under the influence of the polished strip 286 the web assumes a smooth evenly spread condition thus preventing possible wrinkles or uneven stretching of the web which may result in tearing the web.

SEALING MECHANISM DRIVE

The drive mechanism for reciprocating the lower sealing head 52 and the upper sealing head 54 toward and away from each other when a package is properly positioned for sealing will now be described and reference should be made to FIGS. 1, 3, 8, 16 and 17. Referring first to FIG. 3 it will be seen that the lower stretch frame 22 supports a motor 296 which has its output shaft 298 connected to an electromagnetic clutch 300. A speed reducer 302 is connected to the electromagnetic clutch and its output drives, by means of a sprocket chain 304 and sprockets 306 and 308, (FIG. 16) a transverse shaft 310 rotatably received in bearings at 312 (only one of which is shown) secured to brackets 314. On the shaft 310 laterally spaced sprockets 316 are mounted (only one of which appears in FIG. 8) for driving sprocket chains 318 and 320. The sprocket chain 318 is trained about the coplanar sprockets 176a and 216a while the sprocket chain 320 is trained about the coplanar sprockets 176b and 216b. When the clutch 300 is energized effecting rotation of the shaft 310 through the speed reducer 302 and the sprocket chain 304, the chains 318 and 320 are caused to orbit thereby rotating the sprockets on the lower and upper sealing heads 52 and 54, respectively, which by virtue of the cams 178, associated with the lower sealing head 52, and the crank arms 220, associated with the upper sealing head 54 cause translation of the movable portion of the sealing heads toward each other to effect sealing of the overlying webs which contain the product therebetween.

While suitable control means are provided for allowing the sealing heads to dwell in making the seals, the sealing heads of the present invention may be driven toward each other and away from each other without interrupting movement of the chains 318 and 320.

PRODUCT INFEEF ARRANGEMENT

The product infeed structure shown in FIGS. 1 and 20 to 24 which has been described in general terms hereinabove will now be explained in greater detail. The product infeed system conditions the machine control, hereinafter more specifically described, to operate the web feed and the package sealing mechanism. Although a preferred electromechanical arrangement is shown and described, the feed system of the present invention incorporates features which prevent machine operation if the product is not properly located relative to the sealing mechanism 50 and also in the event an object is inadvertently disposed at the discharge end of the infeed table 56.

Referring first to FIG. 20 it will be seen that a guide rod 322 is positioned adjacent one of the lateral edges of the infeed table 56. The guide rod 322 has its ends secured to a stationary post 324, at the entrance or outboard edge of the infeed table 56, and to post 326 located in the vicinity of the discharge end of the feed table 56. Slidably mounted on the rod 322 is a block 328. A link 330 having one end pivotally connected at 332 to the block 328 and the other end pivotally connected at 334 to the sprocket chain 70 serves to move the block 328 along the guide rod 322 when the sprocket chain 70 is in motion. The product pusher bar 78 is also pivotally connected to the block 328 and it has a link or lever 336 rigidly attached thereto. The lever 336 has pivotally connected thereto a swinging link 338 provided at its lower end with a roller 340 rollingly engageable with a cam track 342 which is supported on the infeed table 56 below and parallel to the guide rod 322.

FIG. 22 shows the lever 336 partially broken away to reveal the shape of a slot 344 formed in its end for receiving link 338. The slot 344 includes abutment walls 346 and 348 which limit the degree of pivotal movement of the link 338 relative to the lever 336. FIG. 21 shows the product pusher bar 78 in its fully

retracted position with a tray supported product P on the table 56. When the chain 70 is actuated the upper reach moves in a direction indicated by the arrow. The block 328 moves a short distance rearwardly along the guide rod 322 by virtue of the connecting link 330. As the end of the link 330, which is attached to the chain 70, rounds the sprocket 74, the block 328 is advanced. The roller 340 engages the cam track 342 rotating the links 338 until it encounters the abutment wall 348. As the block 328 advances the pusher 78 engages the product P moving it from right to left toward and onto the conveyor 152. The forward limit to which the pusher 78 is advanced is shown in FIG. 23 wherein the product P is positioned on the conveyor 152 at the sealing station. It will be observed in FIG. 23 that the cam track 342 is inclined at 350 and 352 for the purpose of rotating the link 338 relative to the lever 336. When the pusher 78 is moving from right to left the roller 340 on the link 338 rides on the incline 350 and immediately thereafter loses contact with the cam track 342 causing the link 338 to assume a substantially vertical orientation, the limit of which is determined when the link 338 makes contact with the abutment wall 346 of the lever 336. Continued movement of the chain 70 retracts the pusher 78 and in returning the roller 340 encounters the incline 350 of the cam track 342 thereby raising the pusher 78 to clear another package which has been previously deposited on the infeed table 56. When the pusher 70 is fully retracted the roller rides down the incline 352 lowering the pusher 78 for advancement of another package to the sealing station.

30 To prevent rotation of the block 328 relative to the guide rod 322 the lower surface of the block 328 has rotatably mounted thereon rollers 354 (only one of which is shown in FIGS. 21 to 24), straddling a guide bar 356 mounted on the infeed table 56 directly below the guide rod 322.

35 In order to synchronize web feeding by the stretch frames 22 and 24 with the advance of the package by the pusher 78 limit switches LS-1 and LS-4 are mounted on the undersurface of the infeed table 56 and are actuated in response to movement of the package. In addition limit switches LS-2 and LS-3 are provided which are actuated by one of the rollers 354 carried by the block 328. As shown in FIG. 21 LS-2 makes contact with the roller 354 when the pusher 78 is retracted while the roller 354 makes contact with LS-3 (FIG. 23) when the pusher 78 is fully extended. The manner in which the limit switches are coordinated will be explained in connection with FIG. 29 which shows the schematic of the electrical control circuit.

As shown in FIG. 16 additional limit switches LS-5 and 50 LS-6 are provided for controlling the operation of the sealing heads 52 and 54. These switches are mounted on a bracket 358 suitably secured to one of the brackets 314. The shaft 310 has keyed thereon cams 360 and 362 for actuating, respectively, limit switches LS-5 and LS-6. The cam 360 is formed with a depressed portion 364 while the cam 362 is provided with a projection 366 which determines the sequence of operation of the limit switches LS-5 and LS-6 during 360° rotation of the shaft 310. In describing the overall operation, the sequence and functions served by these cams and switches will be 55 specifically pointed out.

PACKAGING SEQUENCE

In FIGS. 25, 26, 27 and 28 there is diagrammatically illustrated the various steps performed by the packaging machine of the present invention in overwrapping and hermetically sealing a product to be packaged. Referring first to FIG. 25 it will be observed that a product P is moved in the direction of the arrow toward the juncture J of the webs TW and BW while 65 the lower and upper sealing heads 52 and 54, respectively, are retracted. The leading edge of the package encounters the webs at the juncture J and proceeds to the sealing station shown in FIG. 26 where the package is enveloped between the webs TW and BW. As the package moves toward the sealing station the top and bottom webs define a loop. Once the 70

package is properly positioned at the sealing station the sealing heads 52 and 54 are brought into firm engagement to form the seals on the longitudinal edges and the trailing edge of the package while simultaneously forming another seal adjacent the trailing edge seal so as to join the top and bottom webs together to define a subsequent juncture J. Since some waste material is produced by the packaging method of the present invention, which takes the form of strips S, the waste material is taken up on spools 60.

CONTROL CIRCUIT

The description of the over-all operation of the packaging machine of the present invention will be integrated in describing the schematic circuit diagram shown in FIG. 29. Power is supplied to the circuit elements and the motors 66 and 296 by lines L1, L2 and L3. It will be assumed that a package is placed on the infeed table 56 as shown in FIG. 21. To initiate product feed, push bottom PB-1 in line 400 is manually depressed electrically connecting line 400 to L1 and L2 and thereby energizing relay coils CR1 in line 400. Energizing the coil CR1 closes normally open contacts CR1-1 in line L1 and CR1-2 in line 401 which, respectively, energize motor 296 and close a holding circuit for PB-1. With the package or product on the infeed table 56, LS-1 in line 404 is closed and LS-2 also in line 404, is closed since it makes contact with the roller 354. LS-2 connects relay CR6 in line 403 to L1 and L2. Normally open contacts CR6-1 are closed energizing coil CR2 in line 404. Energizing CR2 closes normally open contacts CR2-1 in line 405 and normally open contacts CR2-2 in lines 415 and 416 which connect the motor 66 to lines L1, L2 and L3.

By virtue of the sprocket chain 112, sprockets 126 and 72 mounted on the shaft 128, the sprocket chain 70 commences orbital movement, moving the pusher 78 from right to left as viewed in FIG. 21. As the pusher 78 advances, LS-2 in line 404 switches to its second position, shown in full lines in FIG. 29, to keep the relay CR2 energized. Contacts CR2-1 in line 405 form a holding circuit across the limit switch LS 1, thus maintaining coil CR2 in line 404 energized. As the package is advanced along the infeed table 56 limit switch LS-4 in line 401 closes energizing a clutch coil (clutch 122) in line 401 which connects the web feed drive system to the motor 66. In addition to the energization of the clutch coil in line 401, closing of the limit switch LS-4 also energizes the coil CR5 in line 402 closing normally open contacts CR5-1, also in line 402, establishing a holding circuit across the limit switch LS4.

The pusher 78 continues its movement toward the sealing station until the package P is approximately at the location shown in FIG. 23 on conveyor 152. As the package leaves the infeed table 56 LS-4 opens. When the pusher is to its maximum extended position the roller 354 makes contact with and opens the limit switch LS-3. Opening of LS-3 de-energizes the clutch coil 122 in line 401 and the relay CR5 in line 402 thus stopping the web feed drive. The package P is now disposed between the loop defined by the top and bottom webs. This condition is best illustrated in FIG. 26.

On start up, the heater switch SW in line 412 is closed connecting the seal bar heaters 252 and 268 to the lines L1 and L2. Also, upon energization 268 the relay coil CR1, the converter for seal bar operation is connected to the lines L1 and L2 by line 406a. It is to be realized, of course, that before a package is sealed, the seal bar heaters 252 and 268 are up to temperature as determined by conventional thermocouples connected to meters. After these preconditions have been fulfilled to start sealing of the package located at the sealing station, the toggle switch 409 is adjusted to its run position and the push button PB-3 in line 407 is manually depressed energizing clutch coil 300 also in line 407 through the normally closed relay contacts CR4-1 which are closed when relay coil CR4 in line 413 is energized. CR4 remains energized as long as a photocell 370 is conducting.

Upon rotation of the shaft 310 the limit switch LS-5 is closed by the cam 360 and remains closed for approximately one complete revolution of the shaft 310. Once the limit switch LS-5 is closed the push button PB-3 can be released and the clutch coil 300 in line 407 remains energized through closed limit switches LS-5 and LS-6 in line 409. When the lower and upper sealing heads 52 and 54, respectively, move toward each other, the limit switch LS-6 is actuated by the cam 362 energizing relay coil CR3 in line 408 which closes relay contact CR3-1 in line 411 thus energizing time delay relay TD also in line 411. Also, movement of limit switch LS-6 to its other position, causes the clutch coil 300 in line 407 to be deenergized, thereby stopping movement of the sealer heads 52 and 54. Time delay switch TD-1 in line 410 is normally open. On activation of coil TD in line 411 TD-1 will close after a period of time determined by the setting of the time delay.

After the delay period has expired the time delay switch TD-1 in line 410 closes, energizing the clutch coil 300 in line 407 and the limit switch LS-6 assumes its original position in line 409 de-energizing the relay coil CR3 in line 408. De-energizing the coil CR3 in line 408 opens relay contacts CR3-1 in line 411 which de-energizes the time delay coil also in line 411. The shaft 310 continues to rotate until the cam 360 opens limit switch LS-5 de-energizing the clutch coil 300 in line 407. At this time the sealing heads 52 and 54 are retracted away from each other and the cycle is repeated when a product to be packaged is located on the infeed table in the approximate location shown in FIG. 21.

In certain packaging situations where it is necessary or desirable to provide a more tightly overwrapped product the preferred embodiment can be modified to fulfill such a requirement. FIG. 30 shows a friction drag arrangement which effects longitudinal stretching of the web before lateral stretching occurs. Although the longitudinal stretching mechanism is shown with the upper stretch frame 24, it is to be realized that the mechanism is duplicated on the lower stretch frame 22.

In FIG. 30 the supply roll TWR for the upper web TW has applied thereto a friction drag mechanism indicated generally at 420. This mechanism imparts a retarding force to the web as it is drawn through the machine, thereby stretching of the web longitudinally before it is laterally stretched by the diverging belts 32a and 34a, which correspond to the belts 32 and 34 previously described.

The drive mechanism for the belts and for the web is like that of the modification previously described and the description thereof will not be repeated. In this mechanism the belts 32a and 34a are trained around rear lower idlers 422 then up around two pairs of upper idlers 424, 426 and then down around direction changing idlers 428. This idler modification provides room for the friction drag mechanism 420 which can be of simple construction. A canvas drag belt 430 is anchored at its upper end by an anchor bar 432. The belt extends rearwardly and horizontally, then down around about 90° of the web roll TWR. The belt is tensioned by a drag weight 434. In this manner, unreeling of the web TW from its roll TWR is resisted by the frictional force generated between the drag belt 430 and the partial circumference of the roll in response to the effect of gravity on the drag weight 434. Thus by choosing the friction characteristics of the drag belt 430 and by selecting a drag weight 434, a predetermined degree of frictional retardation and hence a predetermined degree of longitudinal stretching of the web TW can be provided.

FIG. 30A is a side view drawn on a reduced scale of a friction drag assembly of the type just described but adapted for use on the lower stretch frame. In this modification, the lower web roll BWR is retarded by a friction belt 430a anchored to the frame at 432a and stretched by a weight 434a. In order to provide a weighted tension on the belt 430a in the proper direction the belt is trained around frame mounted pulleys 436 and 438 after which the weight 434a hangs from the free end of the belt. The mode of operation of this modification is like that disclosed in FIG. 30.

FIG. 31 is a diagrammatic perspective of a modified installation wherein means are provided for removing or reducing the transverse stretching action on the web provided by the endless belts. In this adaptation a gathering device 440 is mounted on the frame between the upper web roll TWR and the web TW as it passes over the upper stretch frame 24. The function of the assembly 440 is to gather or draw in the edges of the web somewhat as the web leaves the supply roll. Thus the diverging motion of the stretching frame merely removes the previously imparted gather and leaves the web substantially unstretched in a transverse direction. The manner in which this gathering action can be imparted to the web is illustrated diagrammatically in FIG. 31 in the form of a gathering wheel 442 mounted on a free spinning axle 444. The axle 444 is supported in one of a number of vertically spaced positions by means of brackets 446 which are mounted on the frame in any convenient manner. The brackets have axle receiving apertures 448. One of the brackets 446 is removable so that the axle can be placed in selected apertures 448 in the brackets, thereby determining the amount of transverse gathering imparted to the web before it passes over the stretch frame. A gathering wheel (not shown) can also be fitted to the lower stretch frame 22.

Although the best mode contemplated for carrying out the present invention has been herein shown and described, it will be apparent that modification and variation may be made without departing from what is regarded to be the subject matter of the invention.

What is claimed is:

1. A packaging apparatus having a frame structure mounting two rolls of stretchable heat sealable thermoplastic web, said apparatus comprising means engageable with the longitudinal margins of the webs for simultaneously unwinding and transversely stretching each web, said webs following paths merging toward a common plane, sealing means movable in a direction substantially normal to said plane for joining the ends of each web along a transverse line to thereby produce a continuous web, means for feeding products to be packaged toward and against the intersection of said webs and concurrently feeding the webs so that the product being packaged is located in a loop formed by the webs, and means for sealing the loop adjacent the sides and trailing end of the product while simultaneously therewith joining the web by said first mentioned sealing means to produce a continuous web.

2. The packaging apparatus according to claim 1 wherein said means for sealing the web at the sides and trailing end of the product includes web clamping bars having their web engaging surfaces treated so that the web firmly adheres thereto.

3. The apparatus according to claim 1 wherein said web unwinding means comprises frame structures, each frame structure mounting web unwinding and feeding conveyors, means on each of said conveyors for firmly holding the edges of the web, said frame structures being oriented to cause lateral stretching of the web as it is unwound.

4. A method of packaging products in heat sealable thermoplastic film comprising the steps of transversely stretching the film, forming a loop in the film while it is in its stretched condition, inserting an item to be packaged in the loop, and heat sealing the overlying loop portions of the web to produce an overwrapped product, wherein said heat sealing of the loop portions comprises the steps of clamping the overlying web portions together adjacent the edges of the product to relax the tension occasioned by stretching, and sealing and cutting the relaxed portions of the web.

5. Film packaging apparatus comprising laterally spaced, loops of endless web gripping members, means for feeding a web of film into a gripping reach of said members, means for moving said gripping members along for advancing the gripped web, means mounting said gripping members for diverging movement in the direction of web advance along said gripping reach for stretching the web transversely as it is advanced, means for wrapping the articles in the web downstream of said gripping members, and web gathering means upstream of said web gripping reach for drawing the web edges together before they are gripped by said endless members.

6. In a packaging machine of the type which applies a stretch thermoplastic web around a product to be packaged and heat seal the web to enclose the product in the web, the improvement in heat sealing the web comprising means, engageable with the longitudinal edges of overlying transversely spaced web portions, for holding and maintaining said web portions in tension while a product is disposed therebetween; means for clamping the spaced web portions adjacent the margins of the product to be packaged and inwardly of said holding and maintaining means; said clamping means being effective to further stretch the web portions increasing the tension of the web about the product before the spaced web portions are clamped; and means for cutting the clamped webs adjacent the line along which they are clamped to relax the web edges and then heat sealing the web edges.

7. A packaging apparatus having a frame structure mounting two rolls of stretchable heat sealable thermoplastic webs, said apparatus comprising means engageable with the longitudinal margins of the webs for simultaneously unwinding and transversely stretching each web, said webs following paths merging toward a common plane, sealing means movable in a direction substantially normal to said plane for joining the ends of each web along a transverse line to thereby produce a continuous web, means for feeding products to the packaged toward and against the intersection of said webs and concurrently feeding the webs so that the product being packaged is located in a loop formed by the webs, and means for sealing the loop adjacent the sides and trailing end of the product while simultaneously therewith joining the webs by said first mentioned sealing means to produce a continuous web, said web unwinding means comprises anvil blocks having polished surfaces to which the webs firmly adhere.

8. A packaging apparatus having a frame structure mounting two rolls of stretchable heat sealable thermoplastic web, said apparatus comprising means engageable with the longitudinal margins of the webs for simultaneously unwinding and transversely stretching each web, said webs following paths merging toward a common plane, sealing means movable in a direction substantially normal to said plane for joining the ends of each web along a transverse line to thereby produce a continuous web, means for feeding products to be packaged toward and against the intersection of said webs and concurrently feeding the webs so that the product being packaged is located in a loop formed by the webs, and means for sealing the loop adjacent the sides and trailing end of the product while simultaneously therewith joining the webs by said first mentioned sealing means to produce a continuous web, said web unwinding means including anvil blocks having polished surfaces to which each web firmly adheres, and sprocket chains mounting said anvil blocks, said chains travelling in orbits that cause lateral stretching of the webs as the webs are advanced to the product feeding means.
